UNITED STATES PATENT OFFICE

171,852

PAIR OF GOGGLES

George R. Hoffmaster, Esterly, Pa., assignor to
Willson Products, Inc., Reading, Pa., a corpora-
tion of Pennsylvania

Application August 26, 1953, Serial No. 26,587

Term of patent 14 years

(Cl. D57—1)

To all whom it may concern:

Be it known that I, George R. Hoffmaster, a citizen of the United States of America, residing in the city of Esterly, county of Berks, and Commonwealth of Pennsylvania, have invented a new, original, and ornamental Design for a Pair of Goggles, of which the following is a specification; reference being had to the accompanying drawing, forming part thereof, wherein:

Figure 1 is a top, front perspective view, and Figure 2 is a bottom, rear perspective view, with the straps removed, of a pair of goggles embodying my new design.

I claim:

The ornamental design for a pair of goggles, substantially as shown.

GEORGE R. HOFFMASTER.
